Patented Sept. 15, 1925.

UNITED STATES PATENT OFFICE.

LOUIS KRAFT, OF STAUNTON, ILLINOIS.

NETHER GARMENT.

Application filed May 10, 1924. Serial No. 712,402.

To all whom it may concern:

Be it known that I, LOUIS KRAFT, a citizen of the United States, residing at Staunton, in the county of Macoupin and State of Illinois, have invented new and useful Improvements in Nether Garments, of which the following is a specification.

Working men called upon to do heavy lifting and shoveling subject their trousers and other nether garments to great strain, and the object of my invention is the provision of a nether garment so constructed that it is capable of stretching in the crotch and is therefore adapted to last much longer and at the same time be more comfortable to the wearer than is the case when the garment is constructed at and adjacent to the crotch in the ordinary well known manner.

To the attainment of the foregoing, the invention consists in the improvement as hereinafter described and definitely claimed.

In the accompanying drawings, forming part of this specification:—

Figure 1 is a perspective of a portion of a pair of trousers constructed in accordance with my invention.

Figure 2 is a vertical section through my improved portion of the trousers and showing the fly as open.

Figure 3 is an interior perspective showing my improvement.

Figure 4 is an enlarged cross-section taken in the plane indicated by the line 4—4 of Figure 2.

Similar numerals of reference designate corresponding parts in all of the views of the drawings.

The fly portion 1 of the trousers is preferably constructed in the ordinary well known manner as illustrated, and need not, therefore, be described in detail.

In accordance with my invention the crotch portion of the trousers is slotted, as designated by 2, and the portions of the trousers at opposite sides of the slot 2 are reinforced by attached strips 3 in which are eyelets 4 for the reception and engagement of a lace 5 that is designed to have its end portions tied at the front as designated by 6. The strips 4 are preferably connected to the major portion of the garment by stitches 7 in the manner clearly illustrated in the drawings.

Also, in accordance with my invention the lace 5 is elastic in quality, and consequently the crotch portion of the improved garment

is adapted to give or stretch and therefore is not liable to tear or to give rise to discomfort to the wearer. Again because of the slot 2 and the elastic connection of the portions of the garment at opposite sides of the slot 2, the garment is calculated to last much longer than an ordinary garment in which the crotch portion is constructed in the manner extant.

In association with the crotch construction described, I provide a cover 8, attached at 9 to the major portion of the garment, preferably by stitches, and adapted to be detachably secured by snap fastener members 10 and 11 over the slotted crotch. Manifestly, when fastened in closed position as stated, the cover 8 is adapted to exclude dust and is also adapted to contribute to the comfort of the wearer.

At the forward end of the slot 2 I reinforce the garment through the medium of a section 12, of leather, strong cloth or the like, stitched at 13 to the major portion of the garment.

It will be apparent from the foregoing that by virtue of my improvement it is feasible to construct the nether garment of heavy and strong material without liability of the garment breaking in the crotch or being uncomfortable to the wearer.

When my improvement is incorporated in overalls which must of necessity be washed at intervals, the elastic lace 5 is removed precedent to the washing operation, and is replaced after the overalls are dried.

Notwithstanding the practical advantages ascribed to my improvement, it will be readily appreciated that the improvement increases but little the cost of producing a nether garment.

I have entered into a detailed description of my embodiment in order to fully disclose the preferred embodiment of my invention. I do not desire, however, to be understood as confining myself to the specific construction and relative arrangement of the parts inasmuch as my invention is defined by my appended claim, and modifications manifestly may be made within the scope of said claims.

Having described my invention, what I claim and desire to secure by Letters Patent, is:—

A nether garment having a slot in its crotch and also having re-enforcing strips attached to its major portion on the opposite

sides of said slot, the re-enforced portions with snap fastener members for detachable being provided with eyelets and being combined with an elastic lace, a re-enforcing section attached to the major portion of the garment at the forward end of the slot, and a cover of flexible material attached to the major portion of the garment and provided with snap fastener members for detachable engagement with complementary members carried by the major portion of the garment. In testimony whereof I affix my signature.

LOUIS KRAFT.
